UNITED STATES PATENT OFFICE

92,497

DESIGN FOR A GRAVE MARKER

Martin K. Scott, Kansas City, Mo.

Application March 29, 1934, Serial No. 51,240

Term of patent 7 years

To all whom it may concern:

Be it known that I, MARTIN K. SCOTT, a citizen of the United States, residing at Kansas City, Jackson County, Missouri, have invented a new, original, and ornamental Design for a Grave Marker, of which the following is a specification, reference being had to the accompanying drawing, forming a part thereof:—

In the drawing:—

Figure 1 is a front view of a grave marker showing my new design.

Figure 2 is a side edge view of the same.

I claim:—

The ornamental design for a grave marker as shown.

MARTIN K. SCOTT.
